Primary Examiner—Lisa Lichtenstein(74) *Attorney, Agent, or Firm*—Morrison & Foerster LLP(57) **CLAIM**

The ornamental design for a combined ceiling fan housing and light fixture, as shown and described.

DESCRIPTION

FIG. 1 is a perspective view of a ceiling fan having a fan housing, light, and blade irons constructed in accordance with the present invention, the ceiling fan illustrates an environment for said fan housing and light;

FIG. 2 is an enlarged perspective view of a fan housing, light, and blade irons in accordance with the present invention;

FIG. 3 is another perspective view of the fan housing, light, and blade irons in accordance with the present invention;

FIG. 4 is an enlarged top view of the fan housing, light, and blade irons in accordance with the present invention;

FIG. 5 is an enlarged bottom view of the fan housing, light, and blade irons in accordance with the present invention; and,

FIG. 6 is an enlarged front view of the fan housing, light, and blade irons in accordance with the present invention, the side views and the rear view being substantially the same.

The broken line showing of a ceiling fan canopy and blades is included for the purpose of illustrating environmental structure and forms no part of the claimed design.
